UNITED STATES PATENT OFFICE.

LERoy B. TAYLOR, OF CLEVELAND, OHIO.

COMBINED SLIDABLE AND REVERSIBLE WINDOW SASHES.

Application filed May 12, 1924. Serial No. 712,586.

To all whom it may concern:

Be it known that I, LEROY B. TAYLOR, a citizen of the United States, residing at Cleveland, in the county of Cuyahoga and State of Ohio, have invented certain new and useful Improvements in Combined Slid-able and Reversible Window Sashes, of which the following is a specification.

This invention is an improvement upon my Patent No. 1,497,042 dated June 10, 1924, and is directed more particularly to combined slidable and reversible window sashes, the primary object being to provide a construction which will permit of sliding the sashes vertically in the usual manner and in addition reversing them so that they may be readily cleaned or adjusted for ventilation.

Another object is to provide a construction wherein the means of mounting the sashes is such as will permit manipulation of the sashes with a minimum amount of exertion on the part of the operator.

A further object is to provide a combined slidable and reversible window sash having interfitting tongue and groove connection with portions of the window casing or frame, thus providing weather-proof construction.

It is likewise an object to generally simplify window construction and at the same time provide an unusually efficient and durable structure.

Other objects will be in part obvious and in part pointed out hereinafter.

In order that the invention and its mode of operation may be readily understood by persons skilled in the art, I have in the accompanying illustrative drawings, and in the following detailed description based thereon set out one possible embodiment of the same.

Figure 1 is a vertical sectional view of a window constructed in accordance with this invention, the sashes being in closed position;

Figure 2 is a view illustrating one of the sashes in open position and ready for reversing, and the other sash in a partially open position, the arrows indicating the direction of movement of the sashes upon their pivots;

Figure 3 is a sectional view taken substantially on the line 3—3 of Figure 1;

Figure 4 is a sectional view taken substantially on the line 4—4 of Figure 1;

Figure 5 is a fragmentary front elevation partly in section;

Figure 6 is a detail perspective view of the slide and arms which support one side of the sash, and

Figure 7 is a detail perspective view of one of the parting or dividing strips.

Having more particular reference to the drawings throughout which similar characters of reference designate similar parts this invention may be stated as comprising a window casing or frame 10 including the usual vertical chambers 11, in which the sash weights, cords, pulleys, etc., are arranged.

Each outer finishing strip 12, as clearly illustrated in Figures 3 and 4, is provided with an inwardly extending tongue 13 and

between this tongue 13 and the inner wall of the casing, with a rib 14. The tongue 13 is adapted to snugly fit slidably in a vertical groove 15 in a sash whereby to provide a weather proof joint or connection as between the window sash and the casing. It is understood that this mode of connection is put into effect at both vertical sides of the window.

The vertical rib 14 when associated with the dividing strip 16 serves to provide a way or groove 17 wherein I preferably arrange a metal channel or guide member 18 whose function will be herein-after apparent. This channel or guide member 18 as shown, extends the full length

of the window casing, and is secured thereto by screws or other fastening devices.

The lower half of each parting or dividing strip 16 is formed as illustrated in Figure 3. A tongue 19 is arranged to fit within a vertical channel 20 formed in the lower window sash and with a rib 21 which co-acts with a

finishing strip 22 to form a way for the reception of a second channel or guide member 23 which is formed identically with respect to the first named channel or guide member 18. The upper half of the parting or dividing strip 16 is cut down leaving only

a comparatively small rectangular strip 24 whose outer face is arranged in a plane with the outer face of the channel or guide member so as to permit swinging of the sashes and the supporting arms.

The channels or guide members 18 and 23 heretofore referred to have their vertically opposed edges turned inwardly toward each other whereby to provide means for

retaining slide members 25 within the channels. While the channel or guide members 18 and 23 are of the same length as the window casing, the slide members 25 arranged therein are of a length substantially equal to that of each sash and are connected to the sashes through a plurality of arms. Each slide member 25 has its vertical side portions offset and snugly received beneath the inwardly turned side edges of the channel or guide members 18 and 23, thus providing a snug and reliable connection as between these members. These slide members 25 have connection by means of a cord or the like with the usual sash weights. Arranged upon the lower end portion of each slide member 25 is a comparatively small short channel or guide member 26 which receives the outer end of a slidable bolt or guide pin 27 mounted in the adjacent sash. This bolt is provided with a finger or handle portion 28 whereby an operator may readily move the bolt.

Each sash is pivotally connected to one of the slide members 25 by means of a telescopic arm 27'. The tube or housing 28' of this telescopic arm is pivoted to the sash at substantially the midway point of the sash, while the bar 29 is pivoted at its other end to the upper portions of the slide member 25. This bar 29 is provided with a longitudinal slot 30 through which is extended a pivot pin 31 providing connection between this telescopic arm and second arm or link 32. As shown in Figure 2 in the accompanying drawings the telescopic arm 27' may be extended to such a point as to entirely clear the sash of the casing and slides carried thereby, in this manner allowing for rotation or reversing of the position of the sash.

The upper end of the lower sash is preferably of greater width than any of the remaining portions and is provided with a transverse outwardly extended tongue 33 adapted for snugly engaging in a groove 34 formed in the lower inner rail of the upper sash. This connection obviously prevents entry of moisture etc. The upper and lower ends of the upper and lower sashes respectively are provided with weather strips for obvious reasons.

In manipulating this window, the sashes being positioned as shown in Figure 1, the lower sash is first moved substantially to the position shown in Figure 2 whereupon the tongue 33 carried thereby is moved from the path of downward travel of the upper sash. At this point the upper sash is moved downwardly to free it of engagement with the weather strip at the upper end of the casing, after which the window is moved through exerting pressure upon the lower rail in a vertical direction and simultaneously with this movement the upper end of the sash will move toward the operator. During this

operation the sliding bolt or guide pin 27 is sliding in the short channel or guide member 26 and before the position of the sash as shown in Figure 2 can be assumed, the bolts or guide pins must be retracted or disengaged from the guide channel 26. This retraction being effected, the telescopic arm may be extended to its limit as shown in Figure 2 and consequently position the sash so that it may be rotated or reversed as is obvious.

Manifestly, the construction shown is capable of considerable modification and such modification as may fall within the scope of my claims, I consider within the spirit of my invention.

I claim:

1. The combination of a window casing having opposed vertical ways, a slide member arranged in each way, a sash, and telescopic arm and link mechanism connecting the sash and slides whereby to permit vertical sliding and reversing of said sash. 25

2. The combination of a window casing having opposed vertical ways, a slide member arranged in each way, a sash, a telescopic arm pivoted at one end to the upper end of said slide member and at its other end to substantially the medial point of the sash, and a pivoted link connection between the slide member and telescopic arm. 90

3. The combination of a window casing having opposed vertical ways, a slide member arranged in each way, a sash, a telescopic arm pivoted at one end to the upper end of said slide member and at its other end to substantially the medial point of the sash, a pivoted link connection between the slide member and telescopic arms and a separable connection between each slide and the lower part of the sash. 100

4. The combination of a window casing having opposed vertical ways, a slide member arranged in each way, a sash, said sash and slide being of substantially equal lengths, a channel guide member arranged vertically upon the lower portion of each slide member, a retractable guide pin carried by the sash and receivable in said guide member, a telescopic arm pivotally connecting the medial portion of the sash and the upper end of the slide, and a pivoted link connection between the slide member and the intermediate portions of said telescopic arm. 110

5. The combination of a window casing having opposed vertical ways, a channel member arranged in each way and extending the length of the casing, a sash, a slide member arranged in each channel member and being of substantially equal length with the sash, separable connection between the lower end of the sash and the lower portion of the slide member to maintain relative parallel vertical travel of said end of the sash upon the slide member during 120 125 130

part of the opening operation, a telescopic arm connecting the upper end of the slide and said sash, and a pivoted link connecting said slide and the intermediate portion of the telescopic arm.

6. The combination of a window casing having opposed vertical ways, a sash, a slide member arranged in each way, a telescopic arm having one part pivoted to the upper 10 end of the slide member, the second part being pivoted to substantially the medial point of the sash, said parts having a cross pin and longitudinal slot connection, and a pivoted link having one end connected to 15 said cross-pin and the other end to the slide member.

7. The combination of a window casing

having opposed vertical ways, a sash, a slide member arranged in each way, a telescopic arm having one part pivoted to the 20 upper end of the slide member, the second part being pivoted to substantially the medial point of the sash, said parts having a cross-pin and longitudinal slot connection, a pivoted link having one end connected to 25 said cross-pin and its other end to the slide member, and separable slidable connection between the lower end of the sash and each slide member whereby parallel relative sliding between the lower portions of the sash 30 and slide member is maintained during the first steps of opening the sash.

In testimony whereof, I affix my signature.
LEROY B. TAYLOR.
